UNITED STATES PATENT OFFICE.

FREDERICK G. SARGENT, OF WESTFORD, MASSACHUSETTS.

TELEPHONE.

940,284.

Specification of Letters Patent. Patented Nov. 16, 1909.

Application filed March 3, 1909. Serial No. 481,160.

To all whom it may concern:

Be it known that I, FREDERICK G. SARGENT, a citizen of the United States, residing at Westford, in the county of Middlesex 5 and State of Massachusetts, have invented a new and useful Telephone, of which the following is a specification.

This invention relates to telephones, particularly those adapted for wireless use. The power in this class of instruments can be increased up to a certain limit by increasing the number of turns or convolutions of wire about the electro-magnet, but of course this increase is limited on account of the high internal resistance created by increasing the number of turns, and on account of various magnetic and mechanical effects which, as is well-known, are produced in electro-magnets. Particularly in wireless telephony it has been found in practice that a telephone receiver should not have the maximum number of convolutions necessary to produce the greatest motion of the diaphragm armature, but that there is always a certain number of convolutions and therefore a certain resistance which gives the maximum efficiency, this number being determined of course, by the conditions present at any given time. Under the varying conditions in wireless telephony at the present time, a receiving instrument which has been constructed to give the greatest efficiency under the conditions normally prevailing is sometimes called upon to do duty under other conditions in which it does not have a maximum efficiency.

The principal object of this invention is to provide a telephone instrument, particularly a receiver, in which the number of convolutions, and consequently the internal resistance, can be varied at will, so that it can be used under varying conditions with the maximum degree of efficiency in each case.

Further objects and advantages of the invention will appear hereinafter.

Reference is to be had to the accompanying drawing in which—

Figure 1 shows a longitudinal central sectional view of a telephone receiver constructed according to this invention, and Fig. 2 is a diagrammatic view of the windings.

This receiver is shown as comprising a casting 10 in which is mounted a magnet 11 of a well known form, diaphragm 12, and other features of a receiver. One terminal of the electro-magnet is connected by a wire 13 in the casing with a terminal 14 into which

a plug 150 can be inserted or fixed to constitute one conductor from the receiver. The electromagnet is wound in a plurality of coils having several different terminals 15, 60 16, 17 and 18. Each of these terminals is shown in the present instance as provided with a socket into which a plug 20 can be inserted, constituting the other terminal of the device. It will be understood that the wire of which the electro-magnet is wound passes several times around the spool from the terminal 13, and then is brought out to one of the terminals for receiving the plug 20, so that if the plug is introduced 70 into the first terminal, the excitation of the magnet and its internal resistance will be of the minimum degree. The magnet is also provided with an additional winding preferably in series with the first winding and 75 connected with the second terminal for receiving the plug 20, so that if the plug 20 is in the second terminal the current will pass through both of said windings. Thus the resistance and power of the magnet will 80 be increased. In the same way the windings and resistance can be increased by the use of any number of additional terminals for the plug 20, four of which are shown in the present instance. It will be seen therefore 85 that as the instrument will ordinarily be constructed so that for its usual duty some one of the intermediate terminals will be best to use, under any extraordinary conditions where it is found the instrument does 90 not work very well, the operator from his experience can tell whether the plug 20 ought to be moved in such a way as to increase or decrease the resistance, or he can experiment with it until he finds a position 95 for the plug which gives the best results under those conditions.

While I have illustrated and described a preferred embodiment of the invention, I am aware that many modifications may be 100 made therein by any person skilled in the art without departing from the scope of the invention as expressed in the claims. Therefore, I do not wish to be limited to all the details of construction shown, but 105

What I do claim is:—

1. In a telephone receiver, the combination of an electro-magnet having a plurality of coils, a terminal connected in series with all of said coils, a plurality of terminals located in alinement along the shank of the receiver, each connected in series with one of 110

said coils, said coils being connected in series with each other, whereby when a conductor having two terminals is connected with the first named terminal its other terminal can be connected with any one of said plurality of terminals, and one or more of the coils on the electro-magnet will be brought into the circuit in series.

2. In a telephone receiver, the combination of an electro-magnet having a plurality of coils, a terminal connected with all of said coils, a plurality of terminals located along the shank of the receiver, each connected with one of said coils, whereby when

a conductor having two terminals is connected with the first named terminal its other terminal can be connected with any one of said plurality of terminals, and one or more of the coils on the electro-magnet will be brought into the circuit. 15

In testimony whereof I have hereunto set my hand, in the presence of two subscribing witnesses. 20

FREDERICK G. SARGENT.
